COMBINED BRUSH AND SPONGE

Dale H. Ballard, Salt Lake City, Utah, assignor to Deseret Pharmaceutical Company, Inc., Sandy, Utah

Filed Apr. 3, 1967, Ser. No. 6,504

Term of patent 14 years

(Cl. D4—17)

FIG. 1.

FIG. 2

FIG. 3

FIGURE 1 is a perspective view of a combined brush and sponge embodying my new design;

FIGURE 2 is a perspective view of the combined brush and sponge inverted relative to FIGURE 1; and

FIGURE 3 is a fragmentary side elevation thereof.

It is to be understood that the respective bristles partially shown at the upper part and interior of the combined brush and sponge are intended to be continuous throughout the areas encompassed by the broken lines as indicated in FIGURE 1.

I claim:

The ornamental design for a combined brush and sponge, substantially as shown and described.
